UNITED STATES PATENT OFFICE.

ISAAC HOSIER, OF PHILMONT, NEW YORK.

SHINGLING-BRACKET.

SPECIFICATION forming part of Letters Patent No. 606,144, dated June 21, 1898.

Application filed July 21, 1897. Serial No. 645,374. (No model.)

To all whom it may concern:

Be it known that I, ISAAC HOSIER, a citizen of the United States of America, residing at Philmont, in the county of Columbia, in the 5 State of New York, have invented certain new and useful Improvements in Shingling-Brackets, of which the following is a specification.

The invention relates to shingling-brackets, the object being to provide a simple and efficient device for sustaining in place scaffolding or staging for the purpose of assisting workmen in shingling roofs and effectually guarding against accident to the workmen.

The invention consists in a shingling-bracket embodying certain novel features and details of construction hereinafter fully described and claimed.

Figure 1 of the accompanying drawings represents a perspective view of my improved 20 shingling-bracket in open position ready for use. Fig. 2 represents a section of a roof, showing my improved shingling-bracket applied thereto.

The same reference-numerals indicate 25 responding parts in both figures.

This improved shingling-bracket is preferably constructed of a piece of spring-steel bent in the shape of a **U**, as indicated at 1, and comprises a lower arm 2, an upper arm 3, 30 and a connecting-piece 4. The lower arm 2 is pointed or tapered at its extremity to facilitate the insertion thereof beneath a shingle, and said lower arm is provided with a shank or bolt 5, disposed at right angles thereto and 35 made integral therewith. This bolt 5 is adapted to project through an opening 6 in the upper arm 3 of the bracket. After passing through the upper arm 3 the shank 5 is provided with a removable thumb-nut 7, which 40 has a screw-threaded engagement with said shank and by means of which the upper and lower arms of the bracket may be brought nearer together or allowed to move apart. The upper arm 3 of the bracket is bent upward, as indicated at 8, and is then brought 45 backward and returned upon itself to form a depending brace or arm 9, which extends substantially at right angles to both the upper and lower arms of the bracket, thereby forming an 50 abutment against which the board or boards of the scaffolding or staging lie. The arm 9

is provided at its lower extremity with prongs or teeth 10, adapted to penetrate a shingle from the upper side and prevent the possibility of the bracket slipping from its engagement with the shingle, thus obtaining a positive and firm hold upon the shingle. The arm 9 is provided on its front face with a series of projecting teeth or spurs 11, which are adapted to enter the board or boards of the scaffolding or staging and prevent any liability of the latter from slipping.

In operation two or more of these brackets may be quickly and readily applied to the shingles of the roof and securely held by turning the thumb-nuts 7 to cause the spurs 11 to enter the upper side of the shingle and obtain a positive hold thereon. After the brackets are secured in place the boards of the staging or scaffolding may be placed against the arms 70 9, which extend at right angles to the roof.

The bracket above described will be found very effective in practice and is simple and inexpensive in manufacture.

The brackets may be made in various sizes 75 to suit the required conditions, and various changes in the form, proportion, and minor details of construction may be resorted to without departing from the principle or sacrificing any of the advantages of the invention.

I claim as my invention—

1. A shingling-bracket comprising a metallic **U**-shaped body having parallel arms, the end of one of said arms being pointed to 85 adapt it to enter beneath a shingle, the end of the other arm being bent to form an auxiliary **U**-shaped arm extending at substantially right angles to said parallel arms, said auxiliary arm being provided at its extremity 90 with teeth or spurs adapted to engage a shingle, and means for regulating the distance between said parallel arms and for clamping them in any desired position.

2. A shingling-bracket comprising a **U**-shaped body having substantially parallel arms, the end of one arm being adapted for insertion beneath a shingle, and the end of the other arm being bent away from the first arm and then recurved or bent upon itself, 100 and extended toward the first arm and at substantially right angles thereto, the said right-

angular arm being provided at its extremity with teeth or spurs and along its length with laterally-projecting spurs or prongs, and means for regulating the distance between 5 said parallel arms and for clamping them in any desired position.

In testimony whereof I have signed this

specification in the presence of two subscribing witnesses.

ISAAC HOSIER.
